UNITED STATES PATENT OFFICE

WILLIAM O. ASHE, OF ST. LOUIS, MISSOURI, ASSIGNOR, BY MESNE ASSIGNMENTS, TO GENERAL STEEL CASTINGS CORPORATION, OF GRANITE CITY, ILLINOIS, A CORPORATION OF DELAWARE

LOCOMOTIVE STRUCTURE

Application filed January 28, 1929. Serial No. 335,690.

My invention relates to railway rolling stock and consists in a novel locomotive structure, and more particularly in the novel construction of the locomotive framing adjacent to, and the assembly therewith of, the usual engine truck and, preferably, the association therewith of the usual cylinder saddle.

The main object of my invention is to provide for a shallow body center plate thereby eliminating the overturning moment in the center plate which would be attained if a separate center plate were attached directly to the underside of the cylinder casting. I attain this object by providing a locomotive underframing with side members and relatively shallow transverse members between the side members which are adapted to have a separate body center plate attached to the underside thereof, and preferably above the level of the bottoms of the side members.

Another object of my invention is to provide such side members and transverse members with pads on their upper faces for supporting the cylinder saddle casting or castings, thereby providing for very rigid construction and for the transmission of vertical loads directly from the cylinder saddle casting to the transverse members and body center plate, without necessarily transferring the load through the side members.

It is a further object of my invention, in its preferred form, to provide the desired structure in a one-piece locomotive frame or bed casting so as to eliminate the labor and material necessary for securing separately formed members to each other and to eliminate the possibility of play between assembled members due to loosening of the securing means. Such structure also permits the most efficient distribution of metal to secure required strength.

In the accompanying drawings which illustrate a selected embodiment of my invention—

Figure 1 is a top view of one longitudinal half of the forward portion of a locomotive bed, the wheels and a portion of the cylinder casting being indicated in dot and dash lines.

Figure 2 is a side elevation of the same structure showing a portion of the cylinder

saddle casting in section on a plane parallel with and contiguous to the cylinder saddle mounting surface on the side of the bed.

The left hand side of Figure 3 is a section taken on the line 3—3 of Figure 2 and the right hand side of Figure 3 is a section taken on the line 3^a—3^a of Figure 2.

Figure 4 is a longitudinal vertical section taken on the line 4—4 of Figure 1.

Figure 5 is a bottom view of a longitudinal portion of the bed immediately below the center plate mounting elements.

Figure 6 is a vertical transverse section taken on the line 6—6 of Figure 1.

The bed comprises parallel side members 1 each preferably constituting a box-shaped section and having driver pedestals 2 and saddle mounting pads 3 and 4 formed integrally therewith. The side members 1 are connected by top and bottom horizontal webs 5 and 6 whereby the entire bed is substantially box-shaped in cross section. The front end of the bed terminates in a transverse pilot beam 7 extending laterally of the side frames 1.

Parallel transverse members 8 connect side members 1 and preferably have their top surfaces 9 flush with the top surfaces of the saddle mounting pads 4 on the side members. These surfaces 9 also serve to engage the bottom of the cylinder saddle casting 10 and afford support for the same between the sides of the frame.

The bottoms of the transverse members 8 are located a substantial distance above the level of the bottom of the side members and the bottom surfaces 20 serve to mount a body center plate 11 which will extend between the two transverse members 8 and will project downwardly therefrom to engage a suitable truck center plate 12 and be connected therewith by the center pin 13. The bottom wall 6 of the underframe is provided with an elongated recess 14 beneath the center plate carrying members 8 to accommodate the extension of the center plates across the level of the bottom of the frame.

I also desire to provide means for bracing and reinforcing the cylinder saddle casting at a point near its lower wall 10^a and I show

such means in the form of a bracket 16 to which may be bolted the vertical flange 17 on the rear wall 18 of the cylinder saddle. This structure reduces the strain between the bottom and rear walls of the cylinder saddle.

5 The above structure attains, in a very simple and effective manner, the objects set forth in the fore part of the specification. The engagement of the transverse members with the underside of the cylinder saddle practically eliminates any upward deflection of the transverse members due to the thrust of the center plate, and the arrangement of the transverse members is such that the holes 10 15 for the bolts for securing the cylinders or cylinder saddle member can be reamed and the bolts applied without interference.

It is obvious that, in a structure of this type, many of the details may be modified 20 without departing from the essential features of the structure and I contemplate the exclusive use of such variations in detail structure as come within the scope of my claims.

I claim:

25 1. In a locomotive, an underframe having side members, a cylinder saddle supported thereon, a transverse member located between said members beneath said saddle, and a body center plate mounted on said transverse member beneath said saddle.

2. In a locomotive, an underframe having side members, a cylinder saddle supported thereon, a transverse member located between said members beneath said saddle, and a body 35 center plate mounted on said transverse member beneath said saddle and above the level of the bottom of said side members.

3. In a locomotive, a cylinder saddle casting, an underframe casting having side members adapted to support said cylinder saddle casting, spaced transverse elements located 40 between said members and extending below the top thereof, and a body center plate mounted on the underside of said elements.

45 4. In a locomotive, a cylinder saddle casting, an underframe casting having side members adapted to support said cylinder saddle casting, spaced transverse elements extending between said members and located below the 50 top thereof, and a body center plate mounted on the underside of said elements and having upwardly extending elements engaging vertical faces on said transverse elements.

5. In a locomotive, side frame members, a 55 transverse frame member extending between said side frame members, and a body center plate mounted on the bottom of said transverse member and at a higher level than the bottoms of said side members.

6. In a locomotive, side frame members, a cylinder saddle mounted on said side frame members and spanning the space between them, a transverse frame member connecting 60 65 said side frame members below said saddle, and a body center plate mounted on the bot-

tom of said transverse member at a higher level than the bottoms of said side members.

7. In a locomotive, side frame members, spaced transverse frame members extending between said side frame members, and a body center plate mounted on said transverse members and spanning the space between them. 70

8. In a locomotive, a bed having a main portion of substantially box-shaped cross section provided with a substantial opening in its bottom wall, a truck center plate projecting into said opening, a body center plate supported on top of said truck center plate, and transverse members between the side walls of said bed above said body center plate 80 and carried on the same.

9. In a locomotive, a bed having a main portion of substantially box-shaped cross section provided with a substantial opening in its bottom wall, a truck center plate projecting into said opening, a body center plate supported on top of said truck center plate, transverse members between the side walls of said bed above said body center plate and carried on the same, and a cylinder saddle carried on said transverse members in substantial vertical alignment with the interengaging portions of said center plates. 85

10. In a locomotive underframe casting, side members adapted to support a cylinder 90 saddle casting applied thereto, and a transverse member located between said side members and adapted for the application of a body center plate to the underside thereof.

11. In a locomotive underframe casting, side members adapted to support a cylinder saddle casting, a transverse element located 100 between said members and below the top thereof, said element being adapted for the application of a body center plate on the underside thereof.

12. A locomotive one-piece frame casting of box-shaped cross section with a substantial opening in its bottom wall, transverse members above said opening and connecting the side walls of the section, and elements on the lower faces of said members for mounting a body center plate within said structure. 110

13. In a locomotive one-piece frame casting, parallel longitudinal members of substantial depth, parallel transverse members connecting said longitudinal members and of substantially less depth, the tops of said members being flush to provide cylinder saddle supporting elements and the bottoms of said transverse members having surfaces for mounting a body center plate. 115

14. In a locomotive one-piece frame casting, parallel longitudinal members of substantial depth and of box shape in cross section, transverse members connecting the inner walls of said longitudinal members and being of substantially less depth, the tops of said members being flush to provide cylinder saddle supporting elements and the bottoms 120 125 130

of said transverse members having surfaces for mounting a body center plate.

15. In a locomotive one-piece frame casting, parallel longitudinal members of substantial depth, parallel transverse members connecting said longitudinal members and of substantially less depth, the tops of said members being flush to provide cylinder saddle supporting elements, and an upright bracket on each of said longitudinal members at the rear of said transverse members for bracing a cylinder saddle mounted on said elements.

16. In a one-piece locomotive underframe casting, side members adapted to support a cylinder saddle casting and a bracket integral with said side members and extending upwardly therefrom, said bracket being adapted to engage another bracket located on the rear vertical wall of said cylinder saddle casting.

17. In a locomotive, a cylinder saddle casting, a one-piece locomotive underframe casting having side members adapted to support said cylinder saddle casting, said side members having means on the outer sides thereof for securing said cylinder saddle castings thereto, and a bracket integral with said side members and extending upwardly therefrom, said bracket engaging an element on the rear transverse vertical wall of said cylinder saddle casting so as to reinforce said cylinder saddle casting.

18. A locomotive one-piece underframe having a portion for mounting a cylinder saddle and having a recessed lower portion beneath said cylinder saddle mounting portion for mounting a body center plate above the level of the bottom of the frame adjacent thereto.

19. In a locomotive one-piece underframe casting, a main structure having a cylinder saddle mounting portion, and an upright bracket on said structure adjacent to said portion for bracing a cylinder saddle mounted on said portion.

In testimony whereof I hereunto affix my signature this 24th day of January, 1929.

WILLIAM O. ASHE.
